UNITED STATES PATENT OFFICE.

ROBERT H. STROTHER, OF MONTCLAIR, NEW JERSEY, ASSIGNOR TO REMINGTON TYPEWRITER COMPANY, OF ILION, NEW YORK, A CORPORATION OF NEW YORK.

TYPEWRITING AND LIKE MACHINE.

Application filed February 9, 1925. Serial No. 7,937.

My invention relates to typewriting machines, and more particularly to certain improvements in power mechanism for returning the carriage of a typewriting or similar machine.

My invention is in the nature of an improvement on or modification of the carriage return mechanism shown and described in the application of Frederick A. Hart filed 10 Feb. 6, 1925, Sr. No., 7,213, now Patent No. 1,567,590 dated Dec. 29, 1925, and it has for its principal objects to simplify somewhat some of the control mechanism of the Hart machine, and to provide an improved form 15 of safeguard against certain mis-operations of the machine, as will be more fully explained hereinafter.

To the above and other ends my invention consists in certain features of construction 20 and combinations and arrangements of parts, all of which will be fully set forth herein and particularly pointed out in the claims.

In the accompanying drawings,

25 Figure 1 is a left-hand side elevation, fragmentary in character, and with parts in section and parts broken away, of a typewriting machine and carriage returning mechanism having my invention embodied therein.

30 Figure 2 is a front elevation of similar character.

Figure 3 is a fragmentary plan view of some of the mechanism at the front of the typewriter.

35 Figure 4 is a sectional view of some of the mechanism, this figure being more or less in the nature of a leftward extension of Figure 1.

Figure 5 is a perspective view of a part of 40 the mechanism.

Figure 6 is a view in transverse vertical section, on the line 6, 6 of Figure 1 and looking toward the rear.

45 Figure 7 is a detail with parts in section on the line 7, 7 of Figure 1 and looking toward the rear.

50 My invention is shown applied to a Remington No. 12 typewriter. The main framework of this machine includes a base 1, corner posts 2 and a top plate 3 on which are mounted stationary rails 4 along which a carriage 5 is adapted to travel by

means of roller bearings 6. This carriage is equipped with the usual platen and other paper feed devices and it is fed to the left 55 by a spring drum under the control of the usual escapement and, if desired, tabulator devices; but these things are not necessary to be shown in the present case. There is shown, however, at the front of the carriage 60 a margin stop 7 to arrest the leftward travel of the carriage and another margin stop 8 to arrest the rightward travel of the carriage, these being mounted on the front rail or bar of the carriage, or rather on a special toothed 65 bar 10 mounted on said front bar for the purpose. These two margin stops are adjustable by manipulation of handles 11 so as to bring about the arrest of the carriage at any desired letter space position. These 70 stops are the ordinary Remington margin stops except that their abutting parts have been slightly modified to adapt them to the present mechanism; but as far as my invention is concerned, these margin stops can 75 be of any suitable sort.

The Hart carriage return mechanism, on which the present invention is designed as an improvement, includes a rack bar 12 mounted by means of bolts 13 on the under-side of the rear bar or rail of the carriage, the teeth being on the rear edge of the bar and meshing with a pinion 14 mounted on the upper end of a vertical drive shaft 15. The drive mechanism, including this shaft 80 and pinion, is for the most part mounted in a single casting 16 which at its upper end projects through a suitable hole in the top plate 3 and at its lower part is secured, not here shown, to the base 1 of the typewriter 85 frame work. The shaft 15 is journaled at its upper end in the upper part of the casting 16 and at its lower end in a bracket 17 integral with said casting. Loosely mounted on the shaft 15 is a beveled gear 18 in constant mesh with a beveled pinion 20 which is fast on the forward end of a horizontal drive shaft 21, which shaft is suitably journaled in the upright part of the casting 16 and has mounted on its rear end part of a 90 flexible and detachable coupling comprising a disk 22 with pins 23 projecting rearward therefrom. An electric motor 24 is mounted on the rear shelf of the casting 16

and on its armature shaft is mounted a companion part of the flexible coupling comprising a disk 25 having pins 26 projecting forward therefrom. An endless leather band 27 is woven in and out between the pins 23 and 26 and transmits the power of the motor to the shaft 21.

The beveled gear 18 runs between two small rollers or wheels, the upper one, 28, of which is journaled on the reduced projecting end of the shaft 21, this wheel running on a flattened part of the gear and preventing upward motion thereof. Downward motion of the gear is prevented by the other wheel 30, which is journaled on the reduced end of a pin or rod 31 which passes through a suitable hole in the casting 16 and is secured in place by a set screw 32. The hub of the gear 18 constitutes one member 20 of a clutch, said hub having clutch teeth 33 projecting downward therefrom in position to co-operate with clutch teeth 34 projecting upward from the lower clutch member 35. The part of the shaft below the gear 18 is squared and this clutch member 35 is slidable up and down on that part of the shaft. The means for so sliding it comprises a roller 36 running in a peripheral groove in the clutch member 35, said roller 25 being journaled on a pin or stud on the forward end of an arm 37, the split hub 38 of which is secured by means of a binding screw 40 on the right-hand end of a rock shaft 41. Said rock shaft is journaled near 30 said right-hand end in a lug of the casting 16. It will be perceived that the clutch can be closed by rocking the shaft 41. It is so closed by a spring 42 coiled about a rod 43, which rod is pivoted to the lower end of 35 an arm 44 projecting downward from the shaft 41 and being in fact a branch of the arm 37. As shown in Fig. 4 this rod 43 extends rearward into a box-like part 45 of the casting 16 beneath the shelf on which 40 the motor 24 rests, and the spring 42 is compressed between a nut 46 (Fig. 1) on the rod 43 and the front wall of this box so that the power of the spring is exerted 45 to close the clutch.

50 Much of the control mechanism for the carriage return mechanism is included in what may be called a control box 47, this being a cast iron box open at its left-hand side and mounted by means of screws 48 in 55 the outside of the typewriter frame on the left thereof, said screws being threaded into the posts 2 and base 1. In Fig. 1 the upper left-hand part of this box is broken away to show mechanism behind it and the bearing for the left-hand end of the shaft 41 therefore does not show in the drawing, but in the machine said shaft takes a bearing in a rearward extending bracket cast on the box 47 for the purpose. At its left-hand 60 end said shaft has an arm 50 mounted there-

on and secured by a screw 51, said arm extending through a hole made for the purpose into the interior of the box 47. A latch 52 pivoted on a stud 53 inside the box 47 normally engages the forward end of the 70 arm 50 and holds said arm and the lower clutch member 35 down against the pressure of the spring 42. The latch is moved to latching position by a spring 54 secured thereto and to a post 55; when this latch 75 is released said spring closes the clutch and also closes the circuit of the motor.

The motor circuit is controlled directly by the rod 43 which at its rear end normally presses against a block of insulated 80 material 59 mounted on the upper end of a spring conductor 56 having a contact point 57 thereon. The rod normally holds this point away from another contact point 58 mounted on the upper end of another 85 conductor 60. These two conductors 56 and 60 are secured by screws 61 to a block 62 of insulating material fastened to the inside of the chamber 45. When the latch 52 is released and the spring 42, pushing 90 the rod 43 forward, allows the circuit to close at 57, 58 and also closes the clutch, the motor begins to turn and to run the carriage back to the right. It will be perceived that it might sometimes happen that 95 the clutch teeth 34 stood directly beneath the clutch teeth 33 so that the spring would be unable to close the clutch. For this reason the rod 43 is so adjusted as to close 100 the circuit at 57, 58 before the clutch teeth 105 come quite into engagement, with the result that if said clutch teeth should clash as above mentioned, the motor would start nevertheless, and as soon as it did the teeth 33 would move from over the teeth 34 and allow 110 the clutch to close. If the circuit was not closed until after the clutch was closed, the motor would not start at all and the operator might think that the mechanism was 115 out of order.

The mechanism at the front of the carriage for co-operation with the margin stops 7 and 8, includes a rod 63 lying parallel with the run of the carriage, and at its right-hand end journaled in a bracket 64 secured 120 by screws 65 to the stationary front rail 4. This rod extends leftward and at its left-hand end is pivoted at 66 to the upright arm of a bell crank 67, which bell crank is secured by a screw 68 to the end of a short 125 rock shaft 70, which is journaled in a casting or bracket 71, which by means of a screw 72 is secured to the top plate 3. The slide rod 63 projects through the bracket 64 and on its extreme right-hand end there is rigidly mounted an arm 73 which stands in the path of the margin stop 7. This arm normally stands in the position shown in Figs. 2 and 3, a little to the right of the bracket 64, so that in the last letter space step of the car- 130

riage the stop 7 can push said arm a short distance leftward, whereupon said arm and the carriage itself will be arrested by said bracket.

5 A suitable distance to the left of said bracket 64 the slide rod 63 has rigidly mounted thereon another arm 74 which stands in the path of travel of the margin stop 8. In the last part of the return motion of the carriage said margin stop, striking this arm 74, moves it and the rod 63 rightward until said arm and the carriage are arrested by the bracket 64. As will presently appear, means are provided whereby leftward motion of the rod 63 produced by the margin stop 7 trips the latch 52 to set the motor into operation, and means are operated by the rightward motion of the rod 63 to pull down the arm 50 and thus stop 20 the motor and disconnect it from the carriage.

The horizontal arm of the bell crank 67 is pivoted at 75 to the upper end of a link 76, which at its lower end is pivoted at 77 to 25 an arm 78 of a bell crank which also comprises a depending arm 80. Inside the box 47 this bell crank 78—80 has a hub 81 journaled on a transverse rock shaft 82 which is pivoted at its right-hand end in the wall of 30 the box and at its left-hand end in a bracket piece 83 having an angled form shown in Fig. 1 and secured by two screws 84 in mortises in the walls of the box 47. The arm 78 projects out of the front end of the box 35 through a hole made for the purpose.

Said shaft 82 has fixed thereon a hub 85, Fig. 6, having thereon two lever arms 86 and 87 both hanging down and normally inclined rearward from the shaft. The arm 86 40 is of the built-up construction shown in the drawings but this is for reasons connected with certain features of the Hart invention which are not shown herein. The arm 86 has a pin 88 projecting leftward therefrom 45 into the path of the arm 80, the construction being such that when said arm 80 is moved counter-clockwise from the normal position shown in the drawing, its motion will be communicated to the arms 86 and 87; but said arm 80 can move clockwise independently of said arms 86 and 87. Arm 87 has 50 at its lower end a pivot 90 for a long link or bar 91, which extends thence rearward and upward to near the upper left-hand corner of the box 47. At its upper part this link 91 has extending lengthwise thereof a slot 92 through which passes a headed stud 93 projecting fixedly from the wall of the box 47, this stud and slot serving as a guide 55 for the rear end of the link. Near said rear end the link is shaped with a cam edge 94 adapted when the link is pulled forward to act on a roller 95 journaled on a stud projecting from the arm 50. When this bar 91 60 is pulled forward and downward by the arm 65

87, the cam edge 94 acting on this roller depresses the arm 50 to disconnect the clutch and open the circuit.

A spring 96, connected at one end to a pin 97 of the arm 87 and at the other end to a post 98 projecting from the wall of the box 47, restores the lever arms 87 and 86 and the bar 91 to their normal positions. Any suitable means can be provided to arrest the parts in their normal position, that used in the present instance consisting of the end of the slot 92 striking the stud 93. It will be perceived that the motion of the bar under the pull of this spring 96 will be communicated through the pin 88 to the arm 80 and from that back to the slide rod 63 at the side of the carriage.

The means for tripping the latch 52 to set the carriage return mechanism into operation includes a link 100 which at its rear end hooks over a headed stud 101 on said latch, said link being normally urged toward the rear and somewhat downward by means of a spring 102 connected at one end to the link and at the other end to a stationary post 103. The forward end of the link 100 is pivoted at 104 to the vertical arm 105 of a bell crank having also a horizontal arm 106, this bell crank being pivoted on a rock shaft 107, which rock shaft is journaled in two lugs 108 cast on the underside of the box 47, the arm 105 projecting through a suitable hole in the floor of the box. This bell crank has a hub 110 which is loosely mounted on the shaft 107. A fixed post 109 limits the motion of the arm 105 under the pull of spring 102.

The arm 106 is pivoted at 111 to the lower end of a vertical link 112 which at its upper end has a key hole slot 113 in which is a headed stud 114 projecting from the side of the lever arm 78, hereinbefore described. When the parts are in their normal positions the stud 114 is at the bottom of the slot 113, the parts being arrested in that position by the engagement of the arm 105 with the post 109.

It will be perceived that this whole train of linkage, including the slide rod 63 and all the parts connected therewith, are under the control of the two springs 96 and 102, the first of which tends to move the rod 63 toward the left and the other of which tends to move said rod toward the right, and each of these springs acts on parts having limited motion. The result is that the rod 63 stands normally in the intermediate position shown in the drawings where neither of the arms 73 and 74 is in contact with the bracket 64.

The operation of the mechanism will no doubt be plain from the preceding description. When in the leftward travel of the carriage the margin stop 7 encounters the arm 73 and pushes it leftward, the arm 78

is pressed downward, with the result that the arm 80 is moved slightly away from the pin 88 and the bar 91 is not disturbed, but the pin 114 pushes downward on the link 112 and thus trips the latch 52. The arm 50, rising under the pressure of the spring 42, closes the circuit through the motor and closes the clutch, with the result that the carriage is immediately moved toward the right until the margin stop 8 strikes the arm 74 and moves it rightward until arrested by the bracket 64. This rightward movement rocks the arms 86 and 87 and operates the slide bar 91, causing the cam 94 to return to its normal position, thus opening the clutch and circuit. In this operation, the stud 114 on the arm 78, moves upward idly in the slot 113 without disturbing the train of connections to the latch 52.

20 In the Hart mechanism the bell crank 105, 106 is operated by a vertical link similar to the link 112 but longer and said vertical link is operated by a bell crank and another slide rod parallel to the rod 63. By my construction I dispense with this extra slide rod and some of its connections, which results in some simplification of the mechanism. Moreover, Remington typewriters frequently have computing mechanism attached thereto, and said computing mechanism occupies such position as to leave comparatively little room for these parts at the front of the carriage; and dispensing with the additional slide rod is advantageous for that reason.

It is desirable, at least in most instances, to provide a carriage return key and connections to trip the latch 52 in case it is desired to return the carriage before the extreme end of the line is reached. The key for this purpose is here shown almost identical with that employed by Hart. It consists of a lever arm 115 lying outside the main framework of the typewriter just at the right of that forwardly projecting portion of the base 1 which surrounds the keyboard, said lever arm having its forward end formed suitably to be operated by the palm or edge of the hand. The lever 115 has a hub 116 which is mounted on the right-hand end of a rock shaft 117, which rock shaft is journaled at its right-hand end in the base 1 and said shaft extends entirely across the machine through the left-hand part of the base and is connected by a collar and set screw 118 with the short shaft 107, hereinbefore described as being journaled in the lugs 108 and as having the bell crank 105, 106 pivoted thereto. As best shown in Fig. 7, this shaft 107 has a hub 120 fastened thereon by a set screw 121, said hub and the hub 120 occupying the space between the two lugs 108. The hub 120 has rigidly mounted thereon an arm 122 (Fig. 1), and a pin or stud 123 projecting rightward from said arm

lies underneath an arm 124 which is integral with the bell crank arms 105 and 106. The construction is such that when the key 115 is depressed this arm 122 and pin 123 will operate the bell crank 105, 106 and trip the latch 52, but when said bell crank is operated by the link 112 the shaft 107 and the key 115 are not disturbed.

In the Hart mechanism the key lever 115 is guided in a suitable bracket 125 secured by screws 126 to the outside of the base 1, said bracket consisting of a small casting with a slot cut in it to guide the lever and also bored in from the top to make a hole in which is seated a compression returning spring 127. A top plate 128 screwed on to this casting limits the upward motion of the lever. I have not shown this device in all its details for, so far as my invention is concerned any suitable guide and returning spring can be provided for this lever arm.

It has been mentioned that preferably when the shaft 41 is rocked to bring the carriage return mechanism into action, the parts are so timed as to close the circuit before the clutch members have come into engagement. This mode of operation introduces into the mechanism the possibility of a minor mis-operation. When the carriage is restored and the bar 91 is pulled down to its forward position, the cam edge 94 first depresses the roller 95 and then the bar moves a little further, said roller running on the parallel edge of the bar which acts as a dwell. When the operator begins to write on the machine the carriage steps leftward one letter space at a time and the bar 91 moves back toward its normal position in unison with the travel of the carriage, the motion of this bar being of an extent equal to several letter spaces. In the course of this backward travel there will come a time when the dwell part of the cam has passed from over the roller 95 but the cam itself is not completely restored to normal position. If at that time the operator should inadvertently or accidentally depress the key 115 and thereby release the latch 52, the arm 50 would rise but not to its full extent, and it might happen that it would rise high enough to close the circuit but not high enough properly to close the clutch. The motor would then race, having no load on it and the operator might not know just what to do under those conditions. In order to prevent this mis-operation, Hart provided a lock for the latch 52, which lock was controlled by the bar 91 in such fashion that it was impossible to trip said latch until said bar 91 was practically wholly restored to its normal position. In order to avoid injury to the parts under those conditions, Hart provided a flexible or yielding connection between the key lever 115 and the rock shaft 117. One of the features of my invention

tion is to provide an improved means to take care of this contingency without locking the latch 52 and without the necessity for a flexible connection to the key 115.

To this end provision is made for in effect unhooking the link 100 from the stud 101 during the time when the mis-operation above referred to is liable to occur. This can be done in various ways. As here shown, the link 100, where it engages the stud 101, is made with an angled slot 130, said slot consisting of a forward vertical branch and an upper rearwardly extending horizontal branch; and the mechanism is so contrived that normally said link occupies its upper position shown in the drawing where the vertical part of the slot engages the stud and where therefore the link is operative to trip the latch, but as soon as the bar 91 moves forward the link drops down until the horizontal part of the slot engages the stud so that if at that time the key be operated the link will move idly over the stud and will not trip the latch. Said link 100 has a pin or stud 131 projecting rightward therefrom and this pin normally rests on a ledge 132 on the bar 91 and it is this ledge acting on the stud that normally holds the link up in its operative position. When in the return motion of the carriage the bar 91 is pulled forward and downward, the ledge 132 moves away from the pin 131 and allows the link to drop to its lower position where it is inoperative, and this link remains inoperative until in the leftward travel of the carriage, and in about the last letter space step of the bar 91, the ledge 132 again lifts the pin 131 and link 100 to operative position. Preferably the spring 102 has a downward inclination to assist the dropping of the link to its inoperative position. To prevent friction at 101, 130 so as to leave the link free to drop down, is one reason why the stop 109 is provided for the bell crank 105, 106.

As far as I am aware, it is new to have a link or other device, which is designed to set the carriage return mechanism in operation, so connected that it is unhooked and thereby disabled during the first few steps of the travel of the carriage so as to disconnect the carriage return key at that time and thus make it inoperative.

The drawings show a shaft 133 parallel with the rod 63. Said shaft is a part of the Hart mechanism and is not concerned with the present invention.

Various changes may be made in the details of construction and arrangement without departing from my invention.

What I claim as new and desire to secure by Letters Patent is:

1. In a typewriting machine, the combination with a carriage, of carriage return mechanism comprising power operated

means for returning the carriage, a device normally occupying an intermediate position and moved one way from such position by the carriage at the end of its travel in letter feed direction and moved in the opposite direction from normal position by said carriage at the end of its return travel, means operated by the first said motion of said device for bringing the power mechanism into operation to return the carriage, and means operated by the second said motion of said device to put the power mechanism out of operation. 70 75

2. In a typewriting machine, the combination with a carriage and adjustable margin stops, of a device normally occupying an intermediate position and adapted to be moved in one direction from such position by one of said stops and in the opposite direction from such normal position by the other of said stops and in each such motion to arrest the carriage, power mechanism, means operated by the first said motion of said device to bring the power mechanism into operation to return the carriage, and means operated by the second said motion to throw the power mechanism out of operation. 80 85 90

3. In a typewriting machine, the combination with a carriage and two margin stops thereon, of power mechanism, a slide bar having parts adapted to be struck by said margin stop, said slide bar having limited motion in both directions from a normal intermediate position, a spring-restored device operated by one of the said motions of said slide bar for bringing the power mechanism into operation to return the carriage, and a second spring restored device operated by the second said motion of said slide bar for throwing the power mechanism out of operation. 95 100 105

4. In a typewriting machine, the combination with a carriage, margin stops carried thereby, and a motor for returning the carriage, of a spring returned device for bringing said motor into action to return the carriage, a second spring restored device for throwing said motor out of action, each of said devices provided with means to arrest its motion under the power of its restoring spring, and a part connected with both said spring restored devices so as normally to be held thereby in an intermediate position, one of said margin stops moving said device one way from said position to bring the motor into action and the other stop moving said part in the opposite direction from its normal position to throw said motor out of action. 110 115 120 125

5. In a typewriting machine, the combination with a carriage, of motor mechanism for returning the carriage and including a spring closed clutch, a latch normally holding said clutch open, a device adapted when 130

- operated to open said clutch, spring means for restoring said device, means for limiting the motion of said device under the power of said spring means, a spring restored means for tripping said latch, said means having limited motion under the power of its restoring spring, a part held in a normal intermediate position by the two said spring restored devices, a margin stop 10 adapted to move said device in one direction from its said normal position to trip said latch, and another margin stop adapted to move said device in the other direction from said normal position to operate said clutch-opening device.
6. In a typewriting machine, the combination with the carriage and power operated mechanism for returning the carriage, of a carriage returning key, means operated by 20 said key for bringing said power mechanism into operation, said means including a hook-like device, and means for unhooking said device under the control of the carriage so as to render said key inoperative at a certain 25 position of said carriage.
7. In a typewriting machine, the combination with the carriage and power operated mechanism for returning said carriage, of a carriage returning key, means operated 30 by said key through intermediate connections for bringing said power operated mechanism into operation, and means controlled by the carriage through a predetermined portion of its letter-feed travel for 35 breaking the train of connections between said key and said means.
8. In a typewriting machine, the combination with the carriage, of an electric motor for returning the carriage, a drive train from 40 said motor to said carriage including a clutch, a circuit breaker for the motor circuit, a carriage-return key, means controlled by said key for first closing said circuit and immediately thereafter closing said clutch, 45 means operated by the carriage for opening said clutch and circuit, and means controlled by said circuit and clutch-opening means for disconnecting two of the parts operated by said key whereby when said clutch opening means is out of normal position, said key is disconnected from the means whereby 50 it closes the circuit and clutch.
9. In a typewriting machine, the combination with a carriage, power mechanism for 55 driving said carriage, means including a latch 52 for bringing said power mechanism into operation, and means including a bar 91 for throwing said power mechanism out of operation, of a link 100 having hook-like
- connection with said latch, and means 131, 60 132 whereby said bar 91 controls the hooking-up and unhooking of said connection.
10. In a typewriting machine, the combination with a carriage, power mechanism for driving said carriage, means including 65 a latch 52 for bringing said power mechanism into operation, and means including a bar 91 for throwing said power mechanism out of operation, of a link 100 having hook-like connection with said latch, said connection having a part resting on said bar 91 which thereby normally holds said connection hooked up but allows said connection to be unhooked when said bar 91 is operated.
11. In a typewriting machine, the combination with a carriage, carriage return mechanism comprising power-operated means for returning the carriage, spring operated means for bringing said power operated means into operation and a latch for said 70 spring operated means, of a device normally occupying an intermediate position and moved one way from such position by the carriage at the end of its travel in letter feed direction and moved in the opposite 75 direction from normal position by said carriage at the end of its return travel, means operated by the first said motion of said device for tripping said latch to bring the power mechanism into operation to return the carriage, and means operated by the second said motion of said device to move said spring operated means to put the power mechanism out of operation.
12. In a typewriting machine, the combination with a carriage, of carriage return mechanism comprising power operated means for returning the carriage, a device normally occupying an intermediate position and moved one way from such position by 100 the carriage at the end of its travel in letter feed direction and moved in the opposite direction from normal position by said carriage at the end of its return travel, means operated by the first said motion of 105 said device for bringing the power mechanism into operation to return the carriage, means operated by the second said motion of said device to put the power mechanism out of operation, and a key operative only 110 when said device is in its normal intermediate position to bring said power operated means into operation to return the carriage.
- Signed at the borough of Manhattan, city of New York, in the county of New York, 115 and State of New York, this 7th day of February, A. D. 1925.
- ROBERT H. STROTHER.
